UNITED STATES PATENT OFFICE

2,462,227

CONNECTOR

Louis E. Sauer, Sharon, Pa., assignor to Westinghouse Electric Corporation, East Pittsburgh, Pa., a corporation of Pennsylvania

Application October 12, 1944, Serial No. 558,305

4 Claims. (Cl. 287—117)

1

My invention relates to a connector coupling for electrical conductors and, particularly, to such a coupling which will not necessitate disturbing the cable terminals or bushing insulators with which the conductors are associated or require lengthwise movement of the conductor ends in order to connect them.

In cable terminals positioned in switch or pot-head chambers or connected to tap-changing mechanisms in transformers and in similar applications, it is not practical to move the cable lengthwise along its axis in connecting and disconnecting such cables if the cable is of an appreciable size. It has become the common practice, therefore, to loosen or remove the terminal bushing insulators through which the cable conductors are brought into such apparatus when it becomes necessary to connect the terminal conductors within the apparatus. This necessitates the removal of the liquid insulating fluid or oil from the switch or pothead chamber or other apparatus and breaking the gasket seals between the insulator bushings and the casing of the apparatus. A number of instances have occurred where these gasket seals, so removed, have not been properly replaced or the interior of the casing has been contaminated by atmospheric moisture entering through the opening in the casing provided for accommodating the bushing, or by dust or other impurities getting into the casing and causing failure in the electrical apparatus. Furthermore, this practice requires that spare gaskets be provided, since in removing the bushings frequently the gasket is destroyed, requiring that it be replaced by a new one. This practice also requires considerable labor.

It is an object of the invention to provide a connector for electrical conductors in which the conductor ends may be connected without appreciable axial movement of the mating parts and in which a high pressure contact between them is readily obtained.

Other objects and advantages of the invention will be apparent from the following description of a preferred embodiment thereof, reference being had to the accompanying drawing, in which:

Figure 1 is an elevational view of a transformer pothead in which the connector of my invention is adapted to be used with the pothead cover removed;

Fig. 2 is a view, partly in section, showing the two parts of the connector in their disconnected or displaced positions; and

2

Fig. 3 is a view, partly in section, showing the two parts of the connector in their assembled or connected positions.

Referring to Fig. 1 of the drawing, a pothead casing 1 is shown with its cover removed. A three-phase cable 2 enters the pothead casing, through a pressure cone 3. The three separate phase conductors 4 fan out within the pothead and a portion of cable insulation 5 is removed from the end of each cable conductor 6 to permit the attachment of one end of a connector, the other end of which is connected to a terminal stud 8 extending through the terminal bushing 9 of the transformer pothead or switch chamber casing.

The connector 7 is shown in greater detail in Figs. 2 and 3. As shown, the terminal stud 8 comprising the conducting element passing through the bushing 9 terminates in a flat end surface 12. The cylindrical end of the stud 8 is screw threaded, as shown at 13, for a distance back from the end 12 to accommodate a differential nut 14 having a bore centrally therethrough provided with internal screw threads adapted to engage the threads 13 on the stud 8. The differential nut 14 is also provided with screw threads 15 on the lower outer portion thereof that are adapted for engaging the screw threads 16 provided on the interior surface of the bore through coupling nut 17.

A cable terminal 21 is provided forming the end portion of the conducting member of the cable 6 and is soldered, brazed, clamped or otherwise attached to the end of the conductor of cable 6. The upper part of the cable terminal 21 is in the form of a cylindrical stud 22 terminating in a flat surface 23, and is provided with external screw threads 24 that mesh with the threads 16 provided on the inner surface of the bore extending through the coupling nut 17.

When it is desired to couple the two parts shown in Fig. 2 together, the differential nut 14 is screwed back on the threads 13 to expose the flat end 12 of the stud 8 below the lower end of the differential nut, and the coupling nut 17 is screwed onto the stud portion 22 of the terminal 21 to expose the upper end thereof above the upper end of the coupling nut 17. This is the position of the differential nut 14 and coupling nut 17 shown in Fig. 2. The two portions of the conductor to be connected are then moved relatively to each other so that the surfaces 12 and 23 on the ends of the respective studs 8 and 22 are adjacent one another. In the structure shown in Fig. 1, the lower portion

alone is moved to bring the two parts into alignment. The coupling nut 17 is then turned to move upwardly on the threads 24 and to engage the threads 15 on the outside of the differential nut 14 until the surfaces 12 and 23 on the two studs are positioned well between the opposite ends of the coupling nut 17.

Flat surfaces 26 are provided on the coupling nut 17 so that a tool may be applied thereto for this purpose, and flat surfaces 27 are likewise provided on an enlarged portion of the cable terminal 21 so that a tool may be applied thereto to prevent the cable terminal from turning with the coupling nut 17.

Flat surfaces 28 are likewise provided on the upper end of the differential nut 14 for turning this nut, which, when now turned to move downwardly along the threads 13 on the stud 8, while the stud 8, stud 22, and the coupling 17 remain stationary against rotation, operates in a manner to be presently described.

The number of threads 13 per unit length on the inside of the differential nut 14 is greater than the number of threads 15 per unit length on the outside of the differential nut 14. As shown in Figs. 2 and 3, five turns of the thread 15 cover about the same vertical distance as six turns of the thread 13. As a result, the ends 12 and 23 may be placed in proximity within the coupling nut 17, and the differential nut 14 is then turned so as to move downwardly or further into the coupling nut 17, thus moving the end surface 12 downwardly at a rate less than the rate of movement of the nut 14, bringing the surface 12 on the lower end of the stud 8 tightly into engagement with the surface 23 at the upper end of the stud 22. If, as has been assumed for the purposes of illustration, five turns of the thread 15 correspond to the same vertical distance as six turns of the thread 13, then when the differential nut 14 is moved a vertical distance corresponding to five turns of the thread 15, the end 12 of the stud 8 will have been moved a vertical distance corresponding to one turn of the thread 13.

Stated in another way, the threads 13 within the bore of the differential nut 14 have a lesser pitch; that is, they advance a lesser distance per turn of the thread, than do the threads 15 on the outside of the nut 14, so that, for a given length of the nut there will be more turns of the thread 13 than of the thread 15. With this differential pitch of the threads on the inside and outside, respectively, of the differential nut 14, there will result a relative movement between the studs 8 and 22 that is much less than the relative vertical movement of the differential nut 14 and the stud 22. This assumes, of course, that when the nut 14 is so rotated, the stud 8, the stud 22, and the differential nut 17 do not rotate.

It will be appreciated that by the use of the coupling structure disclosed the two cable ends illustrated may readily be connected or disconnected without appreciable axial or vertical movement of either the stud 8 or the stud 22, and that when connected, the tight connection between the surfaces 12 and 23 may readily be obtained.

Modifications in the details of the structure illustrated and described within the spirit of my invention will occur to those skilled in the art, and I do not wish to be limited otherwise than by the scope of the appended claims.

I claim as my invention:

1. In a connector for connecting two conductor elements, in combination, a first conductor ele-

ment to be connected having a flat contact end surface and external screw threads adjacent the flat end surface thereof, a coupling nut having a bore therethrough provided with internal screw-threads adapted to engage the screw-threaded portion of the first conductor element, a second conductor element to be connected also having a flat contact end surface and a screw-threaded portion adjacent the flat end surface thereof, the screw threaded portion of the second conductor element having a smaller diameter than the screw threaded portion of the first named conductor element, a differential nut having a bore therethrough and screw threads on the surface of the bore adapted to engage the screw threads adjacent the end of the second conductor element, the differential nut also having screw threads on its exterior adapted to engage within the bore of the coupling nut, the screw threads within the bore of the differential nut and the screw threads on the exterior of the differential nut having a differential pitch such that when the differential nut is rotated with respect to the two conductor elements and the coupling nut, a relative movement of the end surfaces of the two conductor elements will be effected to bring them into tight engagement or to separate them as desired.

2. In a connector for connecting two conductor elements, in combination, a first conductor element to be connected having a flat contact end surface and a screw-threaded portion adjacent the flat end surface thereof, a coupling nut having a bore therethrough provided with screw-threads internally therethrough adapted to engage the screw-threaded portion of the first conductor element, a second conductor element to be connected also having a flat contact end surface and a screw-threaded portion adjacent the flat end surface thereof, the screw-threaded portion of the second conductor element having a smaller diameter than the screw-threaded end of the first conductor element, a differential nut having a screw-threaded bore therethrough, the screw threads within the bore being adapted to engage the screw threads adjacent the end of the second conductor element, the differential nut also having screw threads on its exterior adapted to engage the screw threads within the bore of the coupling nut, the screw threads within the bore of the differential nut having a lesser pitch than the screw threads on the exterior of the differential nut so that when the differential nut is rotated with respect to both the second conductor element and with respect to the coupling nut the second conductor element will move in the same direction as the differential nut with respect to the coupling nut and at a different rate to effect a relative movement of the flat surfaces on the ends of the two conductor elements to bring them into tight engagement or to separate them as desired.

3. In combination, a connector for connecting two conductor elements each having a cylindrical end portion terminating in flat contact end surfaces for engaging each other, the end portions being cylindrical and having screw threads of different pitch and different diameters thereon, a coupling nut having a bore therethrough and screw threads on the surface of the bore adapted to engage the screw threads of the conductor element having the larger diameter and extending throughout the length of the bore at the same diameter and pitch, a differential nut having a bore therethrough and screw threads on the sur-

face of the bore adapted to engage the screw threads of the conductor element having the smaller diameter and extending throughout the length of the bore, said differential nut also having screw threads on its exterior adapted to engage the screw threads within the bore of the coupling nut, the screw threads within the bore of the differential nut being adapted to engage the screw threads of the conductor element, the difference in the pitch of the threads on the outside and inside of the differential nut being such that when the differential nut is rotated with respect to the conductor elements and the coupling nut a relative movement of the end surfaces of the two conductor elements will be effected to bring them into tight engagement or to separate them as desired.

4. In a connector for connecting two conductor elements, in combination, a first conductor element to be connected having a flat contact end surface and external screw threads adjacent the flat end surface thereof, a coupling nut having a bore therethrough provided with internal screw threads adapted to engage the screw-threaded portion of the first conductor element, a second conductor element to be connected also having a flat contact end surface and a screw-threaded portion adjacent the flat end surface thereof, the screw-threaded portion of the second conductor element having a lesser diameter than the screw-threaded portion of the first named conductor element, a differential nut having a bore there-

through and provided with both external and internal screw threads thereon, the screw threads within the bore of the differential nut being adapted to engage the screw threads adjacent the end of the second conductor element and the screw threads on the exterior of the differential nut being adapted to engage the screw threads within the bore of the coupling nut, the screw threads within the bore of the differential nut and the screw threads on the exterior of the differential nut having a differential pitch such that when the differential nut is threaded about the threads on the second conductor element and into the coupling nut, the second conductor element will be advanced into the coupling nut at a slower rate than that of the differential nut and into tight engagement with the first conductor element.
